Application December 9, 1936, Serial No. 66,392

To all whom it may concern:

Be it known that I, Willard D. Roberson, a citizen of the United States of America, residing at New York city, New York, have invented a new, original, and ornamental Design for a Textile Fabric or Similar Article, of which the following is a specification, reference being had to the accompanying drawing, forming a part thereof.

The figure is a plan view of a textile fabric showing the complete width of the fabric to which

my new design is applied, except for the portion at A, which is similar to that on either side thereof. The dot and dash lines on the drawing outline the design unit, which unit is repeated in regular succession as indicated by the extensions beyond the unit boundaries.

I claim:

The ornamental design for a textile fabric or similar article as shown and described.
